UNITED STATES PATENT OFFICE.

MARIE EUGÈNE MAURICE HAGNAUER, OF PARIS, AND JEAN JOSEPH HIPPOLYTE CREPIN, OF ST.-MANDE, FRANCE.

LAMP-BODY.

1,100,560.

Specification of Letters Patent. Patented June 16, 1914.

Application filed April 17, 1912. Serial No. 691,376.

To all whom it may concern:

Be it known that we, MARIE EUGÈNE MAURICE HAGNAUER and JEAN JOSEPH HIPPOLYTE CREPIN, citizens of the French Republic, residing, respectively, at Paris and St.-Mandé, France, have invented certain new and useful Improvements in Lamp-Bodies; and we do hereby declare the following to be a full, clear, and exact description of the invention, such as will enable others skilled in the art to which it appertains to make and use the same.

This invention relates to lamps, lanterns, projectors and the like and refers particularly to lamps intended for use upon the bodies of ordinary carriages and more especially upon the bodies of motor cars.

The invention is, moreover, particularly suitable for use with that class of such lamps in which a cylindrical device is provided for acting as a lamp carrier and facilitating the mounting of the lamp.

The particular object of the invention is to so construct the aforesaid articles that, contrary to the usual practice, they may be mounted without providing any separate means for carrying them, and to so construct them that they can be mounted upon any surfaces no matter what the conformation of such surfaces may be.

The principle of the invention consists in forming the cylindrical device which, in the usual way serves for mounting the object, from some part of the object itself.

The invention refers more particularly to certain methods of carrying into practical effect the arrangements just mentioned and includes more especially as new industrial products, articles of the kind in question embodying the said arrangements, special parts suitable for making up the articles and carriage bodies fitted with such articles.

The invention will be readily understood with the assistance of the following description and the annexed drawings which are, however, given merely by way of examples of methods of carrying out the invention.

Figures 1 and 2 of the drawing are elevations with parts removed of an electric lamp and an acetylene lamp respectively constructed according to the invention; Fig. 3 is a perspective view on a much smaller scale of the front portion of a motor car with a body of the torpedo type having

mounted thereon two lamps similar to that shown in Fig. 2—only one of such lamps being visible in the figure.

According to the particular method of carrying out the invention illustrated in the drawing in mounting a lantern upon a carriage body we proceed substantially as follows: We provide a cylindrical body which forms the casing *a* of the lamp, that is the portion which contains the working parts, namely the reflector *b* and the lamp or the burner *b*¹. The body may also be formed or provided with a shade or hood *b*². This cylindrical body—which in the case where the lamp is intended for use as an acetylene lamp may also with advantage serve as a support for the burner *b*¹—is of such length that for the purpose of mounting the lamp the rear end of the body can be so cut that it can be fitted to the surface *c* to which the lamp is to be attached no matter what may be the conformation of such surface and may be riveted or otherwise attached with the assistance for instance of tongues *a*¹ formed when cutting away the tube or by means of a turned up or flanged edge produced subsequently to such cutting. By this construction a lamp is produced which can be mounted under all circumstances without resorting to any auxiliary device, a method which is much simpler and much more economical than the present systems: in the case of which when it is desired to mount a lamp with the assistance of a cylindrical lamp carrier it has been necessary to provide a special cylindrical body in connection with the working parts and the container.

What we claim and desire to secure by Letters Patent of the United States of America is:—

1. As a new article of manufacture, a lamp comprising a hollow, approximately cylindrical element which is open at its rear end, is elongated rearwardly, and constitutes the entire body of the lamp, and a light-emitting device and a reflector for the same mounted directly within and secured to the cylindrical element at the front end thereof, the rear end of said cylindrical element being adapted to be cut away to conform to some suitable point on the surface of the body to which the lamp is to be attached, whereby said cut end may be fas-

tened directly to said body at such point and the use of separate supporting devices for the lamp is avoided.

2. As a new article of manufacture, a lamp having its body constituted solely by a hollow, approximately cylindrical element which is elongated rearwardly, the rear end of said elongated portion being adapted to be turned outwardly to produce attaching means conforming to the surface of the body to which the lamp is to be attached at some suitable point on said body, said attaching means being designed to be fastened directly to said body at such point, whereby the use of separate supporting devices for the lamp is avoided.

3. As a new article of manufacture, a lamp comprising a hollow, approximately cylindrical element which is elongated axi-

ally in a rearward direction and constitutes 20 the entire body of the lamp, and a light-emitting device and a reflector for the same mounted directly within and secured to the cylindrical element at the front end thereof, the rear end of said cylindrical element 25 being adapted to be turned outwardly to produce attaching means designed to be fastened directly against the body to which the lamp is to be attached, whereby the use of separate supporting devices for the lamp is 30 avoided.

In testimony whereof, we affix our signatures, in presence of two witnesses.

MARIE EUGÈNE MAURICE HAGNAUER.
